UNITED STATES PATENT OFFICE.

WARREN B. FLANDERS, OF PHILADELPHIA, PENNSYLVANIA, ASSIGNOR TO WESTINGHOUSE ELECTRIC AND MANUFACTURING COMPANY, A CORPORATION OF PENNSYLVANIA.

AUTOMATIC STOP VALVE.

Application filed October 2, 1925. Serial No. 60,132.

My invention relates to operating mechanisms for the emergency valve of a prime mover having an auto stop governor and has for its object the provision of apparatus of 5 the character designated which shall effect a positive quick closing of the valve and an automatic reopening thereof upon resetting of the auto stop governor.

Apparatus embodying features of my invention is illustrated in the accompanying drawing forming a part of this specification wherein Fig. 1 is a view showing an elastic fluid turbine having my improved apparatus applied thereto; Fig. 2 is a sectional view 15 taken along the line II-II of Fig. 1; and Fig. 3 is a diagrammatic view illustrating operating features of the apparatus.

Prime movers, especially elastic fluid turbines, are usually equipped with an emergency valve and an auto stop governor for closing the emergency valve upon over-speeding of the turbine or other abnormal conditions of operation. The emergency valve employed with such apparatus is usually held open during normal operation of the prime mover by some form of releasable means and is biased toward a closing position. When the auto stop governor operates to release the holding means for the emergency valve or such apparatus, it is necessary to reset the auto stop governor and to reopen the valve before the prime mover can again be operated.

In accordance with my invention I provide an emergency valve with biasing means for closing the valve, releasable means for normally holding the valve in an open position and adapted to be actuated by the auto stop governor, and provide fluid pressure operated means for automatically opening the emergency valve when the auto stop governor is reset.

Referring now to the drawings for a better understanding of my invention, I show in Fig. 1 at 10 an elastic fluid turbine having a motive fluid supply conduit 11, said motive fluid supply conduit having disposed therein an emergency valve 12. The emergency valve 12 is preferably of the butterfly type and is normally held in an open position.

At 13 I show a well known form of auto stop governor adapted to operate upon abnormal conditions of operation of the tur-

bine, for example, upon overspeed thereof. The auto stop governor, Fig. 2, embodies a 55 tripping weight 14 located in a diametral recess of the turbine shaft. When the auto stop governor operates, the tripping member 14 moves outwardly and strikes a lever 16 which is, in turn, connected to a link 17 and 60 which releases the means holding the emergency valve 12 open.

The releasable means for holding the emergency valve 12 open comprise a cylindrical guide member 18 which I show mounted rigidly on the motive fluid supply conduit 11 and having disposed therein a floating cylinder 19 (Fig. 3). The guide member 18 and cylinder 19 are preferably located above the emergency valve 12 so that the effect of gravity may cause a quicker closing thereof. However, it will be apparent that the device will operate when placed in other positions than vertically above the emergency valve. 75

The cylinder 19 is normally held in a fixed position with the emergency valve open by a latch 21, connected to a lever 22 which is, in turn, connected to a bell crank lever 23, operatively connected to the link 17. 80 When the tripping weight 14 moves outwardly, striking the lever 16, the latch 21 is disengaged and the cylinder 19 is free to move downwardly in the guide member 18. Disposed within the cylinder 19 is a differential piston 24 having a relatively large stem 26 extending upwardly out of the cylinder 19 through a sleeve 27 with which it makes an approximately fluid-tight fit. The stem 26 serves to reduce the area of the upper side 90 of the piston 24 below the area of the under side thereof. The piston 24 is provided with an orifice 28 which permits a restricted flow of fluid from one side thereof to the other. 85

Fluid under pressure developed by a pump 95 29 is admitted to the upper end of the cylinder 19 by a conduit 31 and flexible tubing 32. Fluid passing into the upper end of the cylinder 19 flows through the restricted orifice 28 into the lower end of the cylinder 19 100 and, with the lower end of the cylinder closed, acting against the greater area of the lower side of the piston 24, forces it upwardly. An exhaust connection 33 located at the lower end of the cylinder 19 leads to an exhaust pipe 34 through flexible tubing 36. 105

Within the exhaust pipe 34 is a valve 37 controlling the flow of fluid from the lower end of the cylinder 19 through said exhaust pipe. The valve 37 is operated by a handle 38 which is connected to the link 17 of the auto stop governor 13.

The emergency valve 12 is operated by a handle 39, said handle having a spring 41 connected thereto. The spring 41 is anchored at 42 and exerts a downward force on the handle 39, or in a direction for closing the emergency valve 12. The handle 39 of the emergency valve 12 is connected to the piston 24 through a link 43 and a stem 44. It will be seen that, with the cylinder 19 in the position shown in Fig. 3, and the valve 37 closed, fluid pressure acting against the greater area of the piston 24 holds it in its uppermost position with the emergency valve 12 open. When the latch 21 is released, the spring 41, assisted by the weight of the cylinder 19, quickly moves the handle 39 of the valve 12 downwardly, effecting a closing of the valve. By the same movement which releases the latch 21 the valve 37 is opened, permitting the fluid under pressure to pass from beneath the piston 24. This passage of fluid, however, need be only at a moderate flow and thus the weight of the fluid, usually lubricating oil, assists in closing the emergency valve 12. In the upper end of the guide member 18, above the cylinder 19, I provide a stop member 46. The stop member 46 acts as an abutment for the cylinder 19 in event of the emergency valve 12 sticking open, when the latch 21 is released and the valve 37 is opened. In such an event fluid pressure acting against the upper face of the piston 24 and reacting against the cylinder 19 forces the piston downwardly, assisting the spring 41 in closing the valve 12. This feature of my invention insures a positive closing of the emergency valve under practically all conditions.

From the foregoing description the operation of the apparatus will be apparent. When the turbine 10 overspeeds, the tripping member 14 moves outwardly, strikes the trip lever 16, pulling the link 17 downwardly, releases the latch 21 and opens the valve 37. Upon release of the latch 21, the spring 41, assisted by the freely moving cylinder 19 with the fluid contained therein, quickly moves the emergency valve 12 to a closed position. Fluid pressure now being relieved from beneath the piston 24, the cylinder 19 is moved upwardly by the fluid pressure acting against its upper end and reacting against the piston 24 to the position it occupied before the latch 21 was released. As soon as the trip lever 16 is moved back to its original or set position, the link 17 is moved upwardly, moving the latch 21 to its position for retaining the cylinder 19, and closing the valve 37. Upon closing the valve

37 fluid pressure builds up beneath the piston 24 and acting against its side of greater area forces the piston upwardly, opening the emergency valve 12. It will thus be seen that upon operation of my improved apparatus, the only resetting required is that of auto stop governor lever 16.

From the foregoing it will be apparent that I have invented an improved mechanism for operating the emergency valve of a prime mover having an auto stop governor, said apparatus being effective to automatically reopen the emergency valve upon resetting of the auto stop governor.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. The combination with a prime mover having an emergency valve, of a cylinder, a piston in said cylinder operatively connected with the valve, means for applying fluid pressure to said piston to retain the valve in open position during normal operation of the prime mover, and means utilizing the weight of the piston and cylinder for closing the valve upon abnormal operation of the prime mover.

2. The combination with a prime mover having an auto stop governor effective upon abnormal operation of the prime mover, of an emergency valve, biasing means for closing the emergency valve, a floating cylinder, releasable means for holding the cylinder in a fixed position with the emergency valve open, a piston within the cylinder for opening the emergency valve when the cylinder is in its fixed position, valve controlled fluid pressure means for operating the piston and for moving the cylinder to its normal position when the admission valve is closed, and an operative connection between the auto stop governor, the releasable means and the valve controlled fluid pressure means.

3. The combination with a prime mover having an auto stop governor effective upon abnormal operation of the prime mover, of an emergency valve, biasing means for closing the emergency valve, a guide member, a cylinder slidably mounting in the guide member, a latch for normally holding the cylinder in a fixed position in the guide member with the admission valve open, a piston within the cylinder for opening the emergency valve when the cylinder is in its fixed position, valve controlled fluid pressure means for operating the piston and for moving the cylinder to its normal position when the emergency valve is closed, and an opera-

tive connection between the auto stop governor, the latch and the valve controlled fluid pressure means.

4. The combination with a prime mover having an auto stop governor effective upon abnormal operation of the prime mover, of an emergency valve having operating means effective for closing said valve when moving in a downward direction, biasing means connected to the operating means for closing the emergency valve, a floating cylinder mounted above the emergency valve, releasable means for normally holding the cylinder in a fixed position with the emergency valve open, a piston within the cylinder connected to the operating means for opening the emergency valve when the cylinder is in its fixed position, valve controlled fluid pressure means for operating the piston and for moving the cylinder to its normal position when the emergency valve is closed, and an operative connection between the auto stop governor, the releasable means and the valve controlled fluid pressure means.
5. The combination with a prime mover having an auto stop governor operable upon a predetermined speed of the prime mover, of an emergency valve, biasing means for closing the emergency valve and exerting a force in a downward direction, a guide member, a cylinder slidably mounted in the guide member above the emergency valve, a latch for normally holding the cylinder in a fixed position with the emergency valve open,

a differential piston having an orifice there-
in located within the cylinder and connected
to the emergency valve for opening said
emergency valve when the cylinder is in its
fixed position, means for admitting fluid un-
der pressure to the cylinder on the side of
lesser area of the piston, an exhaust connec-
tion in the opposite end of the cylinder, a
normally closed valve in the exhaust connec-
tion, and an operative connection between
the auto stop governor, the valve in the ex-
haust connection and the latch for opening the
valve and releasing the latch upon operation
of the auto stop governor.

6. An operating mechanism for an emer-
gency valve of a prime mover comprising
a floating cylinder, a differential piston per-
mitting a restricted flow of fluid thereby
within the floating cylinder and operatively
connected to the emergency valve, means for
admitting fluid under pressure to the side of
the piston having the lesser area, valve con-
trolled means for exhausting fluid from the
opposite side, releasable means for normally
holding the cylinder in a fixed position, and
means responsive to a predetermined speed
of the prime mover for releasing the releas-
able means and operating the valve con-
trolled means.

In testimony whereof I have hereunto sub-
scribed my name this 28th day of September, 1925.

WARREN B. FLANDERS.
